UNITED STATES PATENT OFFICE.

IRA E. McCABE, OF CHICAGO, ILLINOIS.

SAFETY SWITCH MECHANISM.

Application filed November 8, 1926. Serial No. 146,971.

This invention relates to improvements in electrical switches and more particularly to the construction of a temperature control safety switch mechanism.

In industries where high temperatures are used, such as in the reduction and treating of metals and wherever furnaces are employed, requiring a high temperature, it is desirable and in some cases necessary to employ a control which will withstand the high temperatures employed. Most furnaces of this character employ an electrical circuit in connection with the production of the flame or source of heat such as an electrical-
ly operated liquid fuel burner and it is an object of this invention to provide a safety control which will withstand the high temperature of the furnace and positively act to break the electric circuit should the source of heat be discontinued for any abnormal reason.

While the preferred form of this invention is illustrated on the accompanying sheets of drawing it is to be understood that minor detail changes may be made without detracting from the scope thereof.

In the drawings:

Figure 1 is a view in side elevation, with parts broken away, of an embodiment of this invention.

Figure 2 is a view in front elevation looking into the mechanism casing, with the cover removed, and showing the operating mechanism.

Figure 3 is a fragmentary view in section taken on the line 3—3, Figure 2.

Figure 4 is a detail view in cross section of the heating element.

The embodiment of this invention illustrated preferably employs a particular type of mercury tube switch, which is not a part of this invention, as it is particularly adapted to be employed where the actuating element must necessarily be subjected to intensely high temperatures, but the particular construction of the operating parts may be actuated by other forms of thermal control switches.

The device contemplated in accordance with this invention comprises a means for mounting the casing and the operating parts contained within such casing particularly adaptable for employment with a mercury tube switch which comprises a long glass tube or stem 1, closed at one end and terminating at the other end in a tubular member

2 of small diameter. The member 2 is bent downwardly, assuming the stem to be horizontal and then laterally at an acute angle to the vertical and again upwardly to form a V-shaped elbow 3. The vertical arm of the elbow terminates in a bulb or chamber 4 of considerable capacity. The members 1, 2, 3 and 4 may all conveniently be of glass formed into one integral structure. Entering the top of the bulb or chamber are leading-in wires 5, sealed in the glass; these leading-in wires being connected to the upper ends of a pair of long terminals or contact pieces 6 of iron or other suitable material. The members 6 are spaced apart from each other and they extend down into the upper end of the vertical arm of the elbow 3. The leading-in wires are connected to external conductors 7 and 7'. Within the elbow is a small body of mercury 8 sufficient to form a seal, when the pressure on opposite sides thereof is the same, between the two arms of the elbow. The parts are so proportioned that when the mercury is in a position of rest, such as shown in Fig. 2, the pressure in the stem and the chamber 4 being equal, there is a gap between the lower ends of the contact pieces and the top of the mercury; this being the open position of the switch. If the pressure in the stem rises, assuming the device as a whole to be filled with a suitable gaseous medium, the mercury will be caused to flow in a direction away from the stem and toward the bulb or chamber, rising in the vertical arm of the elbow, and engaging with the contacts 6, thus completing the circuit of which the conductors 7 form a part.

This mercury tube switch is operated by inserting the stem 1 within the furnace, or flue leading therefrom, and is usually formed of Pyrex or other glass of a type adapted to withstand high temperatures without cracking or breaking. It is desirable to mount the casing containing the switch mechanism co-operating with this mercury tube switch at a distance from the heat of the furnace which casing must necessarily support the bulb 4. In Figure 1, the wall of the furnace or flue leading therefrom to the stack is indicated by the reference numeral 9. A tubular casing 10 surrounding the stem 1 of the thermal switch is provided with a movable flanged sleeve 11 adapted to be secured thereto by a set screw and the flanges of which are adapted

to be secured to the outer wall of the furnace or flue by any desired means that will rigidly support tubular casing 10 thereon, such as by the anchor bolts shown. The exterior 5 end of the tubular casing 10 terminates at a distance from the exterior wall of the furnace or flue in a circular shield 12 extending at right angles to the tubular casing. This shield supports a spaced-apart circular 10 mechanism casing 13, preferably of less diameter, upon supporting posts 14 secured to both shield and mechanism casing, with the adjacent or rear wall 15 provided with an outstanding tubular casing 16 in alignment 15 with the tubular casing 10 and the outer side provided with a removable cover 17. It is preferable to provide both tubular casings 10 and 16 with resilient supports 18 adapted to yieldingly support stem 1 of the thermal 20 mercury tube switch and allow the casing 13 to be rigidly supported upon the furnace or flue and to be shielded from the heat radiating therefrom.

In assembling the unit the stem 1 is inserted through the tubular casings 10 and 16 with the bulb 4 held in the proper position within the casing by engagement with a spring clip 18 secured to the rear wall 15, as shown in Figure 2. The tubular casing 30 10 is of larger inner diameter than the thermal element 1 passing therethrough and opens through the shield to the atmosphere and through the wall 9 to the interior of the furnace or flue finding sufficient space there- 35 about to allow an induced draft of cool atmospheric air to reduce the transmission of heat from the thermal element and casing 10 to the mechanism casing 13. The parts co-operating with the mercury switch above de- 40 scribed preferably comprise another mercury tube switch 19 of a commercial type having two electrodes or terminals adjacent each other and entering the switch tube adjacent one end, so that when the switch tube is tilted 45 toward that end the mercury therein will close the circuit between the terminals and when tilted toward the other end the mercury will flow away and open the circuit between said terminals. This mercury tube 50 switch is carried in a frame rotatably mounted upon a shaft 20 secured to the rear wall of the casing which frame is provided with a counterweight 21 arranged to normally tilt the switch tube 19 into the open 55 circuit position and the counterweight or frame supporting it is provided with a projection 22 adapted to be engaged by an arm 23 of a manual reset shaft rotatably mounted on the rear wall of the casing having a 60 knurled knob 24 for manual engagement on the rear side thereof, so that upon the operation of the reset device the tubular switch 19 may be rotated about its pivot to assume the closed position. To releasably hold the 65 tilting switch tube 19 in closed position, an

abutment 25 is formed extending downwardly from the switch carrying frame adapted to be engaged by a releasable catch 26 and normally hold the frame with the tube switch 19 in closed position. The engagement between the abutment and catch is preferably made by providing the lower end of the abutment with a set screw, or by bending the extremity at right angles toward the rear of casing wall. The catch 26 is of thermal character and preferably formed of a bimetal strip supported at its lower end in a clamp 27 supported on the rear wall of the casing and so constructed that upon an increase in temperature the upper free end of the catch will move toward the rear wall 15 of the casing and release the abutment to allow the counterweight 21 to rotate switch tube 19 to the open position, and when the temperature is reduced will allow the reset 24 to cause the abutment to wipe over the catch and be again engaged by it to hold the switch tube 19 in closed position.

In order to apply heat to increase the temperature of the bimetal catch 26 to release the rotatable switch tube an electric heating element 28 is attached thereto. This heating element comprises a cylindrical casing 28' insulated with mica or any other insulating material, carried upon the bimetal strip 26 by passing the strip through opposite walls thereof adjacent the rear end and arranging a plurality of compressible carbon or other resistance discs 29 within the casing in contact with each other and with the strip at one end and with a compression member 30, which is insulated from the carbon discs by an insulating disc, at the other or outer end through which the pressure with which the discs bear against each other may be adjusted in any desirable manner, preferably by a rotatable cap on the outer end of the casing having a spring finger 31 adapted to resiliently engage in a series of longitudinal notches 32 arranged about the exterior of the casing adjacent that end and holding the cap in place.

A binding post 33 is preferably carried upon the clamp 27 which supports the lower end of the thermal catch 26 and forms an electrical connection with such strip. Two binding posts 34 and 35 are mounted upon and insulated from the rear wall 15 of the casing below the catch binding post 33. The binding post 34 is connected by a lead 35¹ to the series of discs 29 adjacent the pressure block 30. One terminal 6 of the thermal actuated switch bulb 4 is connected to the binding post 34 by a lead 7 and the other terminal 6 of this switch is connected by a lead 7¹ to the binding post 33 upon the thermal catch 26, which binding post 33 is in turn connected by a lead 36 to one terminal 130 of the tiltable switch tube 19. The other

- terminal catch is connected by a lead 37 to the binding post 35. The binding posts 34 and 35 are connected by leads 38 and 38¹ passing out through the bottom of the casing 5 to the circuit to be controlled.
- The terminals 6 within the bulb 4 of the thermally actuated mercury tube switch are, therefore, in a shunt circuit which when closed by the mercury 8 within the bulb 4 10 reduces the strength of the current of the main circuit, sufficiently so that the current passing through the heating element 28 will not generate enough heat to cause a movement of the catch 26. When the circuit is 15 opened between the terminal 6 in the bulb 4, then the full strength of the current of the main circuit passes from binding post 35, through lead 37, switch 19, and lead 36 to binding post 33, thence through bi-metal 20 strip 26, heating element 28, lead 35¹, to binding post 34. The rotatably mounted mercury tube switch 19 acts as a safety switch because, when the main circuit to the control is closed during the normal operation 25 of the electrically operated heat producing device with which it is associated, and for any reason the device does not produce such heat or, having once done so it should then fail to continue such production, the circuit 30 between terminals 6 in bulb 4 of the thermal switch will be broken by the reduction of the mercury 8 in bulb 4, causing the full strength of the current of the main circuit to be caused to pass through the heating element 35 28 and rotatable switch 19 and the heat generated thereby within the element 28 will be transmitted to the thermal catch 26 causing it to move out of contact with the abutment 25 and allow the counterweight 21 to rotate 40 switch 19 to break the circuit therethrough.
- During the normal operation of the electric heat producing device with which this device is adaptable to be employed the main circuit may be opened and closed independently 45 of this device any number of times without affecting the operation of such device but when once the main circuit is broken within this device the heat producing device cannot be caused to operate until 50 the safety switch 19 has been moved by the reset 24 into the closed position.
- What I claim is:
1. A safety switch comprising a thermally actuated switch and a mechanically actuated switch connected in series in the circuit to be controlled, said latter switch having mechanical means normally acting to open said switch, and a releasable catch to hold said switch in closed position provided with 55 electric means in a shunt circuit for releasing said catch, said latter means provided with a manual adjustment to regulate the amount of the current passing therethrough, whereby when both switches are closed the current 60 of the circuit to be controlled passes through both switches, and when the thermally actuated switch is open the full strength of the current passes through the shunt and mechanically operated switch, energizing the electric controlling means to release the 70 catch and allow the mechanical means to operate the switch to break the circuit therethrough.
  2. A safety switch comprising thermally actuated and mechanically actuated switches 75 in series in the circuit to be controlled, said latter switch having mechanical means normally acting to open said switch, and a releasable catch to hold said switch in closed position having a manually adjustable electric means in a shunt circuit for releasing said catch, whereby the amount of the current passing through the shunt may be regulated to adapt the safety switch quickly to various strengths of current of the main 80 circuit after assembling the device.
  3. A safety switch comprising a thermally actuated and a mechanically actuated switch in series in the circuit to be controlled, a thermally actuated catch adapted to hold the latter switch in closed position, and a heating element co-operating therewith in a shunt circuit with said switch comprising a plurality of super-imposed resistance discs in 85 said shunt circuit and manual means in connection therewith to vary the pressure with which said discs bear against each other.
  4. A safety switch comprising a plurality of switches in series in the circuit to be controlled, including a mechanically operated switch, said latter switch having mechanical means normally acting to open said switch, a thermally actuated releasable catch normally holding said switch in closed position, and a manually adjustable heating element 90 in a shunt circuit mounted upon said catch.
  5. A safety switch including a mechanically operated switch in a circuit to be controlled having mechanical means normally acting to open said switch, and an electrically controlled releasable catch in a shunt circuit normally holding said switch in closed position, comprising a bi-metal strip and a manually adjustable electrical resistance element controlling the amount of the current required to generate sufficient heat to 95 actuate the thermal catch to release the mechanically operated switch in the main circuit.
  6. A safety switch comprising a thermally 100 actuated switch and a mechanically operated switch in series in the circuit to be controlled mounted in a casing in connection with a thermally actuated releasable catch for the latter switch in a shunt circuit, the thermal member of said first switch passing through and extending beyond said casing and adapted to be extended within the walls surrounding a heat producing element, means surrounding said thermal member adapted to 105 110 115 120 125 130

4
be secured to said walls and supporting at a distance therefrom a shield for said casing, and means carried upon the shield to support the casing at a distance therefrom and from the said means surrounding the thermal member.

7. A safety switch comprising a thermally actuated switch and a mechanically operated switch in series in the circuit to be controlled, mounted in a casing in connection with a thermally actuated releasable catch for the latter switch in a shunt circuit, the thermal member of said first switch passing through and extending beyond said casing and adapted to be extended within the walls surrounding a heat producing element, means surrounding said thermal member adapted to be secured to said walls and supporting at a distance therefrom a shield for said casing, means carried upon the shield to support the casing at a distance therefrom and from the said means surrounding the thermal member, and resilient means mounted within the casing and mounted within the shield supporting means to yieldably en-

gage and position the thermal member extending therethrough.

8. A safety switch comprising a thermally actuated switch and a mechanically operated switch in series in the circuit to be controlled, mounted in a casing in connection with a thermally actuated releasable catch for the latter switch in a shunt circuit, the thermal member of said first switch passing through and extending beyond said casing and adapted to be extended within the walls surrounding a heat producing element, means surrounding said thermal member adapted to be secured to said walls and supporting at a distance therefrom a shield for said casing, means carried upon the shield to support the casing at a distance therefrom and from the said means surrounding the thermal member, the means surrounding the thermal element between the walls and shield forming a draft conduit from the shield into the heat producing element for reducing transmission of heat from the heat elements to the mechanism casing.
